UNITED STATES PATENT OFFICE.

ROBERT BALMER, OF TORONTO, ONTARIO, CANADA.

METHOD OF DESTRUCTION OF REFUSE.

Application filed September 22, 1919. Serial No. 325,431.

To all whom it may concern:

Be it known that I, ROBERT BALMER, a subject of the King of the United Kingdom of Great Britain and Ireland, and a resident 5 of the city of Toronto, in the Province of Ontario, Dominion of Canada, have invented certain new and useful Improvements in Methods of Destruction of Refuse, of which the following is a specification.

10 This invention relates to methods of destruction of the refuse of cities and to apparatus particularly adapted to carry such methods into effect, which said apparatus forms the subject-matter of my copending 15 application, filed October 18, 1919, Serial Number 331,669, entitled "Apparatus for the destruction of refuse."

These inventions have for their general objects the provision of means capable of receiving, storing, treating, handling and burning the waste of municipalities, composed in large part of wet fuel and the attainment of these objects without creating a nuisance, either by sights or smells offensive to the 25 community. More particular objects are the provision of a semi-automatic plant of high efficiency capable of being economically constructed and operated and adapted to reduce by combustion the heterogeneous refuse 30 to be destroyed to a substantially homogeneous form of clinker adapted for use in building, road making, and the like purposes, and to ash and flue dust adapted for utilization as an ingredient of agricultural 35 fertilizers. Other specific objects of my inventions are the provision of storage capacity for refuse prior to its combustion in crowded localities and the treatment of it there in a sanitary manner, whereby in a 40 limited area the waste of the municipal district may be destroyed without offense to the neighborhood, and whereby both the economy of short haulage is obtained and the expense of a large investment for land 45 is avoided. Further objects will appear as they are hereinafter developed.

In the attainment of the above recited objects and others, as subsequently set forth, my inventions more particularly consist in 50 the method of destruction of mixed waste, comprising the several steps, first, of classifying the waste with respect to combustibility; second, separately storing and treating the waste as thus classified; third, building up a fire by successive additions of waste through 55 the range of classification from those most

readily combustible to those of least combustible character; and, fourth, increasing the efficiency in combustion by utilizing high temperatures maintained substantially constant throughout.

In the attainment of the first step of the method above set forth, I employ a series of bins; and in pursuance of the objects of the second step I independently treat the waste 60 as thus separately stored by pre-heating at regulable temperatures varied in accordance with the character of the waste and the quantity of moisture content therein; and in pursuance of the third step of the above recited method I first employ waste of high fuel value to kindle the fire upon the combustion grate and when a fire bed is thus formed, introduce the more refractory fuels thereupon until a bed of clinker has accumulated and then superpose upon it, those wastes of least combustible character.

The apparatus preferably utilized in carrying out my described methods is shown in the accompanying drawings, in which like reference numerals are employed to designate similar parts throughout the several figures, and in which

Figure 1 is a horizontal cross-section upon the line I—I of Figure 2, showing in plan 85 a refuse destructor composed of four bins and a series of five combustion units adapted to cooperate therewith.

Figure 2 is a vertical cross-section upon the line II—II of Figure 1.

Figure 3 is a vertical cross-section upon the line III—III of Figure 1.

Figure 4 is a vertical cross-section upon the line IV—IV of Figure 2.

Figure 5 is a vertical cross-section upon the line V—V of Figure 2.

Figure 6 is a perspective view of an air valve controlling device associated with one of the combustion units.

Figure 7 is a vertical cross-section upon the line VII—VII of Figure 1.

Figure 8 is a vertical cross-section upon the line VIII—VIII of Figure 1.

In these figures the numeral 1 indicates a floor or platform termed a tipping floor for the discharge of the refuse carts or vans 52. 2, 2 are openings in the tipping floor fitted with suitable covers 4, 4. 3, 3 are rails or guides provided to preserve the alignment of the carts or vans with the openings 2. The covers 4 are provided with swinging props 5 adapted to hold the covers in raised posi-

tion when open. 6, 6 are the refuse storage bins and 6^a the division walls or partitions between these bins. 7, 7 are the discharge openings from the storage bins provided with sliding doors 8, 8 for closing these openings, the sliding doors being protected by dependent walls or baffles 9, 9 from the pressure of the stored refuse. Each of these doors 8 is provided with a chain and hand ring 10 to raise and lower them, the chain running over the guide pulleys 11. 12, 12 as shown in Fig. 4 are hot air chambers beneath the storage bins, and 13 (Fig. 3) is a valve in an inlet pipe, not numbered, for the admission of cool air to the hot air chamber 12. 14 is a lever adapted to control the inlet air through the pipe and valve 13. 15, 15 are air exhaust pipes or flues leading from each bin, and connecting with a pipe or flue 16 and in turn connected with pipe 17 leading to the exhaust inlet of the fan or ventilator 18 which is driven from the pulley 67 and is adapted to exhaust the air and gases from the refuse storage bins and to deliver an air supply for the furnace ash-pits 26^a and combustion chamber 32. 19 are auxiliary hot air chambers surrounding the flues 15, 16, 17 and fan 18, connecting at the openings 20 with the hot air chambers 12, 21 and 21 is the opening connecting the hot air chamber 12 with the exhaust air pipe 15. 22 is the pressure inlet from the fan 18 communicating with the pipe or flue 23 to the pipe or flue 24. 24 is a connecting pipe or flue serving the inlet air pipes 25 to the individual ash-pits of the combustion units 26 which are preferably adapted to roll upon tracks 71. The combustion unit 26 comprise a fire grate 28, an ash-pit proper 26^a, having ash-pit discharge door 26^b and an air inlet 26^c regulated by a valve 27 controlling the air supply to the individual ash-pit. The fire grate 28 preferably has sloping dead plates 29 surrounding the perforated bed of the fire grate.

Preferably, a battery comprises a series of five units 26, as shown, adapted to move as a train in the continuous furnace chamber 30. This furnace chamber is common to all the units whose fire grates are engaged in active combustion. In the structure shown the train of these fire-grates so engaged comprises four units, the fifth unit being employed in the discharge of its contents and while so employed being outside of the furnace chamber 30 and located in the finishing chamber 30^a whither the consecutive units 26 are withdrawn from the furnace chamber and left to complete the combustion of their contents and to cool off their clinker before exit to the open air, and thereafter to be returned to the furnace chamber 30 through the transfer chamber 30^b, seen in Figures 4 and 5.

65 31 are the outlet flues from the furnace

chamber 30 to the combustion chamber 32. This combustion chamber has the crown 33 and extends beneath the three bins whose contents are of the less combustible character, the crown 33 being of decreasing thickness to afford greater heat to the bins whose contents have the higher moisture content, the crown being thinnest beneath that holding the bin containing the wettest fuel, usually garbage. 34 is the outlet flue from the combustion chamber 32 to the main smoke flue 35; the main smoke flue 35 is of such length as will afford opportunity for the settling out of the flue dust. It leads to the boiler 36 which is preferably located vertically above the bins in order to economize space where land values, as in city limits or where population is dense, make compactness desirable. The boiler is provided with the outlet 37 leading to the chimney 38. The boiler 36 affords means for the generation of steam to be utilized in the power plant, not shown, for suitable application to such needs for power consumption as the driving of the suction blower 18 and the operation of the hydraulic motor hereinafter described.

The air pipe or flue 23, connects with the pipe 39 leading through or over the crown 33 of the combustion chamber and has an outlet into the combustion chamber near the points of entrance to said chamber of the flues 31 which lead from the furnace chamber 30. 40 is a regulating valve and manual control therefor limiting the amount of air to be supplied through the pipe 39. 41 is a compressed air main having the branches 42, leading into the storage bins 6. The pipes 42, of which four are shown for each bin, are of unequal length upon their horizontal runs, the longest extending to the back of the bins. Each pipe terminates in an upward bend, extending to unequal heights, forming a stepped series, from the highest at the back of the bin, to the lowest, which is nearest the front. Each of these pipes is connected to a cross-head pipe, extending the width of the bin. These cross head pipes are provided with flat horizontal nozzles or mouth pieces 44, seating between and under successive separated steps 53, constituting a terraced incline forming the bottom of the bins 6. 45 is a lever controlling the valve for regulating the entrance of compressed air from the main pipe 41 to the horizontal branch pipes 42, cross head pipes 43 and the nozzles 44 for the purposes hereinafter described.

46 are the feeding hoppers to the furnace chamber 30. These hoppers have dumping bottoms 47 shown operatively in Fig. 5 and comprising the horizontal sliding cover 48 having a ratchet frame by which the hopper bottoms are opened and closed through the medium of the cog wheel 49 and shaft and chain 50 and hand wheel and cog gear 130

51, as shown in Fig. 2. Upon rotation of the cog wheel 49 the sliding cover 48 is withdrawn permitting the bottom 47 to drop and the contents of the hopper to feed to the 5 furnace. The sliding covers 48 are preferably of vitrified material.

As shown in Figure 2 spy holes 54 are provided for inspection of the fire grates and to permit the trimming of fuel thereon.

10 As shown in Figure 7, 55 is a furnace entrance door provided with a pulley and chain gear 56 (Fig. 5). 57 is a shuttle truck for carrying the empty fire grate and ash-pit unit into the furnace 30. This truck runs 15 upon the rails 61 at the entrance end 30^b of the furnace.

58 is the furnace exit door provided with pulley and chain gear operating same 59, 60 is the shuttle truck for removing the 20 clinker laden fire grate and its ashpit from the finishing chamber 30^a. 62 is the track for the shuttle truck at the exit end of the furnace. 63 is a hoisting gear for lifting the fire grate and ash-pit combination when 25 the clinker and ash are to be discharged from the same. This hoisting gear is operated from the overhead trolley 64. The clinker and ash are discharged from the fire grate and ash-pit upon the belt conveyor 30 65. 66 is the track connecting the outgoing and incoming tracks and upon which the combined fire grate and ash-pit is adapted to run. 68 is a tool for hauling the fire grate from the furnace 30 to the finishing chamber 35 30^a, in which finishing chamber is located a coil of water tubes 69 affording water circulation for taking up the waste heat from the hot clinker. The fire grate units are moved as a train through the furnace 30 by 40 means of the hydraulic motor 70 which is adapted to push the fire grates from the entrance end of the furnace to the exit end as a train of grates preferably adapted to roll upon a track as stated, but which may be 45 moved therethrough by any suitable mechanism manually operated or by gravity. I prefer, however, the track 71 as shown and the hydraulic motor 70.

The individual ash-pits 26^a are served by 50 the air pipes 25 through the medium of a connecting sleeve 72 cooperating with the air inlet 26^c of each ash-pit, as shown in detail in Figure 6, in which 72^a is an arm between the sleeve 72 and the extended shaft 55 of a butterfly check valve 77 operated through the medium of a rocking shaft 73 having a slotted arm 74. The rocking shaft 73 is connected by the arm 76^a, with the arm 83 at the end of the rocking rod 78 60 having a fixed arm 79 carrying a snubbing rod 80. The rocking shaft 73 is connected to the hydraulic motor 70 through the connecting rod 76 and the slotted guides 75. The spring 81 is attached to fixed point 82 65 and to the arm 83 at the end of the rocking

rod 78. This spring when free to act by release of the rod 80 closes the butterfly check valve 77 when the motor is operative to move the fire grates progressively forward, thus shutting off the supply of forced draft to the fire boxes automatically, the valves being opened again by the engagement of the fire boxes with the snubbing rod 80 upon the movement of the sleeves 72, to connected position between the air supply pipes and the air inlets.

The method of operation of the apparatus above particularly described in carrying out the processes of this invention, is substantially as follows:

In the collection of municipal refuse and waste certain districts afford characteristic classes of materials, one district preponderating in ashes, another in garbage, and another in waste materials of inflammable character. No attempt is made under the method of collection with which my invention is preferably employed, for selective collection but this fact of distinctive character of municipal waste according to the districts 80 where it is gathered, is taken advantage of at the arrival of the vans or carts at the destructor where the carts 52 are dumped into bins selected in accordance with the usual and known character of the load. The general character of the refuse of a given district determines the necessary number of bins, but average conditions encountered are most efficiently handled by the provision of four bins admitting the classification of 85 waste into four grades. The most readily combustible waste is deposited in the first bin, which thus contains readily combustible material of high fuel value, such as paper, wood and the like. Waste of greater or less 90 fuel value and of heterogeneous character is disposed of in the second bin. The materials of less combustibility and considerable moisture content are disposed of in the third bin, and refuse predominantly consisting of 95 garbage is dumped in the last bin.

The refuse carts or vans arriving at the tipping floor or platform are preferably guided by rails or other suitable devices and proceed in file to discharge their contents through the openings in the floor into these refuse storage bins below. The various bins forming the battery are preferably kept separate, as shown, by sealed partitions or division walls. The covers to the openings in the tipping floor are provided as shown to swing against the direction of the carts' travel and have swinging props hinged into their top surfaces which fall out by gravity when the cover is removed past the 115 vertical, thus acting as a support for the cover and inclining it toward the opening in which position it affords a chute for the discharged waste. The refuse when deposited in the bins, even when the latter are par- 120

tially filled, passes largely by gravity toward the discharge openings through which it is drawn into the feeding hoppers as required. These bins are fixed storage chambers having a frontage corresponding with that of the furnaces but relatively of great depth from front to back. This enables the height of the storage chamber to be kept within desired limits. When the refuse lies too far back from any opening to fall by gravity to or near such opening, the workmen by operating one of the lever controlled valves can introduce from the compressed air main, through one of the branch compressed air pipes connecting with the nearest cross head pipe, a blast of compressed air through the nearest flat horizontal mouth pieces or nozzles set in and extending across the floor of the refuse storage bin. The floor of the bin, as shown, is constructed with a downward slope toward the discharge opening, with a series of inclined treads 53, whereby the removal or loosening of frictional contact with the floor by the insertion of the air blast below the refuse and parallel with the floor is practicable and this united with the impulse given by the blast itself starts a forward sliding movement of the refuse which is accelerated by the weight and momentum of the refuse so that with the removal or lessening of the restraining friction it tends to fall by the natural effect of gravity. As indicated by dotted lines in Figure 2, the refuse is roughly divisible into layers or columns whose inclination is that of the angle of slip of the material. It will be found that the effect of the air blast from the nozzles nearest the removal opening is limited to the outermost layer or column of refuse which is inclined roughly at an angle of 45° toward the rear of the bin and whose depth or thickness varies with the weight and texture of the refuse and the depth from front to back of each inclined section of the floor affected by the blast. By operating in succession the first or nearest set of nozzles, and then the second, and then the first two and the third, and so on, the whole of the refuse is progressively brought forward to the discharge opening with a combined sliding and rolling movement of the mass along its exposed surfaces. During the actual operation of the compressed air blasts from the nozzles, the sliding door of the discharge opening is preferably kept closed, the movement of the doors being free from interference by contact with the mass of stored refuse due to the baffle plates.

As above pointed out an essential and important part of the work of a destructor is the regulation of the service of cart and van discharge. For reasons heretofore pointed out, it is desirable to deposit the more easily combustible refuse in the bin located above the entrance end of the furnace chamber and

the least combustible refuse in the bin nearest the opposite end of the furnace. It is desirable to follow the same rule of distributing the more combustible refuse with respect to each individual bin where provision is made for a double line of discharge openings, that is to say, one set of openings in the fore part and another in the rear of the storage chambers. 70

Assuming that the distribution of the refuse from the carts to the storage bins has been effected accordingly, the waste will then be substantially graded according to its combustibility as to individual bins as well as to the battery of bins. 75

In order to raise the temperature and otherwise improve the combustibility of the refuse while in the storage bins, the bottoms of these are heated from a hot air chamber which derives its heat principally by radiation from the crown of the combustion chamber. Inasmuch as the moist refuse is preferably stored in proportion to its moisture content as far as possible in the bins farthest removed from the entrance of the furnace chamber, a progressively thinner crown is provided over the combustion chamber as illustrated in the drawings, the crown being shallower as the distance from the entrance of the furnace chamber is increased. Where so large a moisture content exists as in garbage and ordinary city refuse, the application of heat to that material while in storage makes it give up in vapor a portion of that moisture, thus improving its fitness for combustion in the furnace. At the same time the inflammable character of the other classes of refuse is increased by the application of heat. Alcohol and ether are rapidly formed, absorbing in their formation a considerable quantity of moisture and increasing by this double action the combustibility of the refuse. At the same time many hydrocarbons are volatilized by the heat and pass off along with the water vapor and alcohols and ethers with the fan exhaust as above described. The oxidation of metals in the warm, moist atmosphere of a storage bin is rapid, releasing appreciable quantities of hydrogen by decomposition of the water, thus adding to the gaseous combustible elements blending with the air supply to the fan. The inflammability, however, of the alcohol, ether and unstable volatilized hydrocarbons, combined with the hydrogen, free and nascent oxygen and other gases and vapors, is so great that care is needed in the application of heat and its graduation according to the necessities of each case. Hence the provision of a graduated heat supply to the hot air chamber and means of cooling of the chamber in an emergency by the inlet pipe and valve above described, which for greater safety may, if 80 85 90 95 100 105 110 115 120 125 130

desired, be automatically controlled by any usual thermostatic apparatus. It will be noted that the compressed air pipes 42, 43, and the compressed air nozzles 44, are 5 heated by the hot air chamber 12 so that the air blasts ejected below and amongst the refuse will contribute effectively toward warming and drying the refuse while also loosening, opening up and aerating same, 10 thus further improving the conditions for combustion.

In the initial operation of the destructor the first fire grate unit is charged from the storage hopper above the first bin where 15 inflammable fuel is afforded. The work of charging is performed by the workman discharging the storage bin, whose duty it is to keep the feeding hopper full of refuse. The emptying of the feeding hopper, however, is the duty of the fireman on the floor 20 below. By means of a hand wheel 51 connecting by chain and cog wheel 50 and cog wheel 49 with the ratchet frame and horizontal sliding cover 48, the fireman opens 25 the crown of the furnace and at the same time the bottom 47 of the feeding hopper 46 falls and the charge of refuse is dropped by gravity into the furnace. By reverse motion of the hand wheel, the sliding cover 30 lifts the bottom and closes simultaneously the opening of the furnace and the bottom 35 of the feeding hopper. The material best suited for initiating combustion having thus been deposited, the fire is kindled upon the 40 fire grate unit. Each unit combines in itself the fire grate and ash-pit suitably mounted with wheels on a track running from end to end of the furnace chamber. The course 45 of each grate in its passage through the furnace chamber is from the entrance door to the exit door. After initial firing with the fuel from the first bin, the grate is moved to its position under the next following feed hopper. When so moved the fire 50 grate already has a fire nucleus with which to burn less combustible refuse and thus to form a thicker bed of hot clinkers with which to deal with the more refractory refuse supplied from the remaining storage 55 bins of the battery. When the last charge of refuse upon this fire grate unit has been consumed, its particular run is finished and the unit is removed to the finishing chamber where, after having its position adjusted through the opening and by a suitable tool, the mass of hot clinker on the fire grate is cooled by a further application 60 of the air blast from air pipe 25 and air inlet 26 and the waste heat given off from the clinker is absorbed by the nest of water tubes set below the crown of the finishing chamber. Each fire grate and ash-pit unit undergo the same series of operations as 65 every other unit. These units together constitute a train which moves as an entirety.

At the entrance end of the furnace chamber each unit rests on a shuttle truck and in the finishing chamber extending beyond the opposite end of the furnace chamber another shuttle truck is provided to receive 70 each unit in turn.

The movement of the fire grate and ash-pit units through the furnace chamber is intermittent but constitutes a continuous operation. The units are moved through 75 the furnace preferably by a hydraulic motor, each thrust of which is for the full length of one unit, thus carrying the whole series of four units over the same distance. On the withdrawal stroke of the motor 80 space is left accordingly for the introduction of one empty unit at the entrance end of the furnace chamber. This empty unit is afforded by the return unit which has been emptied of its clinker and returned to 85 track 66 and run to track 61 where it is received by the shuttle truck and conveyed through the furnace entrance door. On passing through this entrance door, the unit again stands within the furnace chamber 90 under the first feed hopper and is ready to repeat the cycle of operations already described beginning with firing with the most combustible class of refuse and progressing through the successive charges each of more 95 refractory material.

As it is desirable to break connection with the air blast and the ash-pit of each unit at each change of position of the unit, suitable arrangements for that purpose are provided, one of which is illustrated in the drawings as the preferred form, as already described. The varying nature of the refuse successively charged into each combustion unit and the increasing depth of the fire bed continuously formed, render separate treatment of the units desirable as to the amount and pressure of air to be supplied thereto. In order to secure operative conditions independently controllable, the 100 ash-pits are preferably formed separately and integral with each separate grate, as has been pointed out. The same result may be less efficiently secured, however, by fixed ash-pits below the moving fire grates with 105 partition walls brought up into such close proximity to the fire grate frames as to minimize the loss of air between the crevices. 110

For the correct regulation of the pressure and amount of air supply to the ash-pit of each unit, the valves 27 are provided for manipulation by the fireman at each of the points of stoppage of the units in their passage through the furnace chamber and in the finishing chamber.

The air supply for combustion in the furnace chamber comes under pressure from the pressure outlet of the fan. A further supply of air under pressure is delivered by the fan through the special flues which pass 125 130

through or over the crown of the combustion chamber into the latter. By its passage over the combustion chamber the air in this supplementary supply becomes highly superheated and serves to assure the complete combustion of gases issuing from the furnace chamber into the combustion chamber. While the fan thus delivers the air supply to the ash-pits and for supplementary combustion in the combustion chamber, it draws its own supply through pipes or flues which connect with pipes or flues opening in the upper part of the storage bin and thereby exhausting the air and such moisture-containing fumes and gases therefrom as arise from the refuse.

By the provision of the auxiliary hot air chamber 19 and the setting in the brick work or masonry of the air pipes or flues, protection is afforded against heat losses. By maintaining the temperature of the air fumes, vapors and gases exhausted from the storage bins and preventing the condensation, particularly of the volatilized hydrocarbons, as well as other vapors in the pipes and in the fan, its continuity of operation is secured and the loss of valuable gaseous fuel for the furnace is prevented. This condensation would otherwise deposit a viscous tarry substance in the pipes and flues and fan interfering with their efficiency and requiring a stoppage of the plant for cleaning at intervals.

By making the fire grates movable laterally through a furnace chamber common to all, each unit passes through the same zones as every other fire grate and each of the firing operations takes place at one and the same point for all the units of the group. This arrangement permits such a distribution of the refuse in storage as will enable the furnace to work most efficiently in combustion and also as to labor cost and conservation of heat, the final result being shown in higher temperatures, larger output and lower operative cost.

The structural advantage obtained in this arrangement of fire grate service is that only two doors are required for each battery of furnaces, namely, one for the entrance and the other for the exit of the grates. The whole face of the furnace is thus completely free of doors for either furnace or ash-pit service. There are only a few small openings through which tools may be entered for the dressing of the material upon any one of the fire grates. This construction tends not only to strengthen the whole furnace structure but also to reduce the heat losses by radiation. Similarly the discharge of the ash and clinker at one end of the furnace instead of from separate furnace doors tends to reduce and simplify the transport service of the clinker and ash while not interfering with the work

of attending to the other fire grates of the same battery.

In the destructor described no air currents or gaseous products of combustion or of fermentation leave any part of the destructor in a free volume at any time save through the stack or chimney. The arrangement provides at every point for an indrawing of air wherever there is an external opening to atmosphere save at the ultimate point of release, namely, the chimney. The preheating of the garbage in the storage bins may be thus carried on at the high temperatures necessary to the wettest class of fuel, since the constant ventilation of the bin is accomplished and these gases and vapors drawn off continuously. The air passages along which the volatilized hydrocarbons are conveyed from the bins to the furnace are maintained at a temperature higher than that of the bins themselves. By this arrangement condensation in the fan, flues and pipes is avoided and the volatilized hydrocarbons are delivered entire to the furnace for passage through the fire grate or to the combustion chamber for destruction therein. The means shown for maintaining this temperature higher than that in the storage bins comprises the enclosure of the air flues and fan itself in a chamber which is itself heated by the flue leading from the combustion chamber, but the same results may be otherwise accomplished as by the direct injection of superheated air by which volatilization of the hydrocarbons is maintained and their condensation prevented.

By the closed circulation system described, the practical difficulties previously encountered through premature condensation in the pipes or flues are overcome and the loss of valuable combustibles is prevented as well as the extra work in cleaning the pipes and flues, compulsory stoppage of the furnace fans or ventilators and consequent depreciation in efficiency of the plant as a whole.

By the methods above set forth and described, a marked increase in efficiency is secured in rate of combustion, temperatures obtained, the economy of labor and cost of management. The sanitary conditions of the destructor, both for the workmen engaged in its operation and for the community where it is installed, are resultant features of advantage that permit the operation of a destructor in the midst of a densely populated district without detriment or inconvenience to the inhabitants. This possibility affords great economic advantages since the community producing the refuse may destroy it within its own immediate area, thus avoiding transportation of refuse for long distances with the increasingly unpleasant odors inevitable from the rapid fermentation and decomposition of garbage.

Having thus described my invention and the preferred embodiment thereof, but not desiring to be understood as limiting its scope otherwise than as particularly defined in the appended claims, I claim:

1. In the incineration of refuse, the method of progressively firing consisting in utilizing the highly combustible waste as an initial charge, forming a fire bed from less combustible waste thereon, and successively dumping fixed charges of waste of lessening degrees of combustibility upon the fire bed after it becomes established.

2. In the incineration of garbage, the method of reducing the moisture content preliminary to charging said garbage into a combustion chamber, consisting in storing said garbage in a receiving bin, there pre-heating it for such period and at such temperature that fermentation is actively promoted and until alcohols and ethers form in substantial quantities, separating such vapors and garbage, and then drawing off such vapors from the bin.

25 3. In the incineration of garbage, the steps preliminary to charging same into a combustion chamber consisting in separately storing said garbage in a preheated chamber; forcing currents of heated air under pressure through the mass; continuing such aeration until the garbage generates a gaseous mixture of water-vapor and fermentation-products of inflammable character; withdrawing the garbage from said chamber and separately burning said gaseous mixture and utilizing the heat of its combustion to heat said storage chamber.

4. The method of incineration of municipal waste consisting in grading the waste with reference to its combustibility, separately storing the several grades, preheating the several grades at temperatures proportional to the moisture content of the grades, and progressively burning same in a common fire, the progression being through the successive grades from that of readiest combustibility to that of least combustibility.

5. The method of destruction of waste including wet fuels consisting in grading the waste with reference to its combustibility, initially charging a grate with waste of readiest combustibility, firing same, adding thereto material of less combustibility but adapted to form a fire bed, successively charging such grate with waste of decreasing combustibility, and intermittently progressing said grate to receive each successive charge, and repeating the series of operations upon succeeding grates travelling in a continuous series through a common firing chamber to produce a cycle of constant operation.

6. In the incineration of municipal refuse

containing garbage, the method of promoting the combustibility thereof consisting in separately storing the garbage; raising the temperature thereof to the point of conversion of the water thereof into vapor; aerating the mass with air under pressure; continuing to heat and aerate same until the alcohols and ethers generated have combined with the water-vapor and then charging the dehydrated mass into a separate combustion chamber.

7. In the destruction of garbage and the like refuse having a high moisture content, the method of rendering same combustible consisting in storing same in a closed chamber other than the combustion chamber, applying heat thereto and simultaneously forcing currents of air under pressure throughout the stored mass and continuing such treatment by heating and aeration until the moisture is vaporized, the unstable hydrocarbons are volatilized and products of fermentation are formed in such quantities as to render the gaseous mixture of water-vapor, volatilized hydrocarbons, alcohols, ethers and air highly inflammable

8. In the destruction of municipal waste, the method of preparation thereof for incineration consisting in separately storing the material of garbage content in a preheated chamber adjacent to but not a part of the combustion chamber; maintaining such garbage at such temperature as will force rapid fermentation thereof; withdrawing the volatile products created by such temperatures; separately burning said products and causing the combustion thereof to heat said chamber.

9. In the destruction of municipal waste, the method of preparation thereof for incineration consisting in separately storing the material of garbage content in a preheated chamber; maintaining such garbage at such temperature as will force rapid fermentation thereof; withdrawing the volatile products thus created; separately burning same; separately burning said garbage, and causing the combustion of said withdrawn volatile products to promote the burning of said garbage.

10. In the destruction of municipal waste, the cycle of operations consisting in charging garbage into a preheated closed bin; storing it there until fermentation products are generated in sufficient volume to supply an inflammable gaseous mixture; conducting a part of such mixture to a combustion chamber and there igniting same; utilizing the heat of such combustion to maintain the temperature of said bin; conducting another part of such gaseous mixture to an incinerating grate, and there igniting same; discharging the garbage from such chamber upon said grate, and promoting the incinera-

tion of said garbage by the burning of said gaseous mixture.

11. The steps in the method of disposal of municipal refuse preliminary to incineration consisting in grading such refuse relatively to the combustibility of the classes of waste comprised therein, and separately storing the several grades.

12. The steps in the method of burning municipal refuse consisting in building up a fire-bed from waste of progressively decreasing combustibility, the waste of greatest combustibility being first employed, and waste of less combustible grades being successively dumped in layers thereon as the preceding layer becomes capable of support-

ing the combustion of a less combustible grade.

13. The steps in the method of destruction of municipal waste consisting in establishing a series of movable fire-beds, and feeding graded fuels cumulatively to each from a succession of feeding points.

14. The steps in the method of destruction of municipal waste consisting in establishing a series of separate fire-beds, successively feeding said fire-beds with fuel of predetermined combustibility, and progressively advancing said fire-beds to a common discharge point.

ROBERT BALMER.
